United States Patent Office

Des. 182,674
Patented Apr. 29, 1958

182,674

LUGGAGE FASTENER OR THE LIKE

Abraham Levine, Mendham, N. J.

Application March 22, 1956, Serial No. 40,727

Term of patent 14 years

(Cl. D10—7)

Fig. 1

Fig. 2

Fig. 3

Fig. 1 is a face view of the luggage fastener or the like, with its members engaged, showing my new design;

Fig. 2 is a side edge elevational view of the luggage fastener or the like as illustrated in Fig. 1 and

Fig. 3 is a top end elevational view of the same.

I claim:

The ornamental design for a luggage fastener or the like, as shown.
